Primary Examiner — Garth Rademaker*Assistant Examiner* — Fitzgerald L Butac(74) *Attorney, Agent, or Firm* — Woods Oviatt Gilman LLP; Katherine H. McGuire, Esq.(57) **CLAIM**

The ornamental design for the irrigation injector, as shown and described.

DESCRIPTION

FIG. 1 is a front perspective view of an irrigation injector of our new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

1 Claim, 4 Drawing Sheets(56)
